ATTORNEY

WITNESS:

UNITED STATES PATENT OFFICE.

WILLIAM L. SHELTON, KANSAS CITY, MISSOURI.

SEAT ANCHOR.

Application filed May 6, 1925. Serial No. 28,476.

This invention relates to a seat anchor and more particularly to an anchor for a theater seat and has for its primary object the construction of an anchor that besides rigidly holding the seat in position will have additional advantages.

An object of the invention is the novel manner of securing the anchor in place and providing an inclined or perpendicular front 10 wall and an inclined back wall to form a rest for the feet and to also facilitate cleaning between the seats.

Besides the above my invention is distinguished in the novel manner of constructing 15 and shaping the anchor so as to have many advantages hereinafter set forth.

With these and other objects in view the invention will be better understood from the following description taken in connection 20 with the accompanying drawings, wherein:

Fig. 1 is a fragmentary sectional detail view of a floor illustrating the invention associated therewith, in anchoring position 25 with respect to a chair, fragmentarily illustrated, and

Fig. 2 is a perspective view of a chair illustrating the invention associated therewith.

26 The seat anchor embodying my invention is indicated generally by a reference character 5 and is adapted to be associated with a chair 1 comprising the usual cast iron legs 1'.

35 The seat anchor 5 is adapted to be associated with a floor 3 defining a channel 4.

My improved seat anchor comprises a body substantially triangular in cross section defining a base 7 bent to provide a substantially U-shaped rib 6 which is adapted to snugly fit in the channel 4. This anchor 5 further defines side walls 8 and 9 tapering upwardly and inwardly toward each other as best illustrated in Fig. 2, to a point contiguous the bottom side of the seat 7' of the chair 1. The anchor 5 may be formed of any approved material which will best serve the purpose.

45 As best shown in Fig. 2 of the drawing the legs 1' define feet 2.

The anchor above described is associated with a chair 1 and the floor 3 in the following manner.

The anchor 5 is disposed beneath the seat

member 7' with the feet 2 of the chair positioned upon adjacent portions of the base 7 on opposite sides of the rib 6. This is accomplished by springing the lower end portions of the legs 1' a sufficient distance apart to permit the disposition of the anchor 5 between the legs 1' beneath the seat member 7'. After this has been accomplished the rib 6 is forced inwardly into the channel 4. In this position of the anchor 5 with respect to the chair 1 and the floor 3 it will be manifest that transverse movement of the chair with respect to the channel 4 will be prevented by reason of the engagement of the rib 6 in the channel 4.

By tapering the side wall 9 in the direction illustrated in the drawing this side wall will provide a convenient foot rest for the person occupying the chair (not shown) to the rear of the chair illustrated in the drawing. The side wall 8 will prevent the occupant of the chair 1 from swinging his foot toward the rear of the chair into contact with the feet of the person occupying the chair to the rear of the chair as illustrated in the drawing.

The anchor being disposed between the legs 1' will prevent articles from rolling beneath the chair toward the front thereof.

While I have illustrated and described the preferred form of construction for carrying my invention into effect, this is capable of variations and modifications without departing from the spirit of the invention. I, therefore, do not wish to be limited to the precise details of construction set forth, but desire to avail myself of such variations and modifications as come within the scope of the appended claim.

I claim:—

The combination with a floor having a channel formed therein, of a chair anchor defining a base portion providing a rib adapted to snugly fit in the channel, said chair anchor being adapted to be disposed between opposite legs of a chair with the feet of the legs disposed upon adjacent portions of the base, said anchor defining side walls extending upwardly and inwardly toward each other to a point contiguous the under side of the seat of the chair.

In testimony whereof I affix my signature.

WILLIAM L. SHELTON.
